CLAIM

The ornamental design for a packaging container for wet tissues or the like, as shown and described.

DESCRIPTION

FIG. 1 is a perspective view of a packaging container for wet tissues or the like showing my new design; FIG. 2 is an exploded perspective view showing the lid separated from the container; and FIG. 3 is a top plan view of the container without the lid.

The bottom is plain and unornamented.

FIG. 2.

FIG. 3.
